UNITED STATES PATENT OFFICE

94,710

DESIGN FOR AN EMBLEM

David C. Rockola, Chicago, Ill.

Application December 10, 1934, Serial No. 54,378

Term of patent 14 years

To all whom it may concern:

Be it known that I, David C. Rockola, a citizen of the Dominion of Canada, residing at Chicago, in the county of Cook and State of Illinois, have invented a new, original, and ornamental Design for an Emblem, of which the following is a specification, reference being had to the accompanying drawing, forming part thereof, and in which the single figure is a perspective view of an emblem showing my new design.

I claim:

The ornamental design for an emblem as shown.

DAVID C. ROCKOLA.
